US0D1102743S

(12) United States Design Patent (10) Patent No.: US D1,102,743 S
(45) Date of Patent: * Nov. 25, 2025

(54) HANDBAG

(71) Applicant: MANUFACTURE JD, Paris (FR)

(72) Inventor: Ramesh Nair, Paris (FR)

(73) Assignee: MANUFACTURE JD, Paris (FR)

() Term: 15 Years

(21) Appl. No.: 29/935,110

(22) Filed: Mar. 29, 2024

Related U.S. Application Data

(62) Division of application No. 35/516,070, filed on Jan. 27, 2022 (U.S. filing date under 35 U.S.C. 384), and having an international filing date of Jan. 27, 2022, now Pat. No. Des. 1,035,268.
